UNITED STATES PATENT OFFICE.

GEORGE L. ROLLINS, OF BRIDGEWATER, MASSACHUSETTS, ASSIGNOR TO—W. H. McELWAIN COMPANY, OF BOSTON, MASSACHUSETTS, A CORPORATION OF MASSACHUSETTS.

REINFORCED INSOLE.

1,026,225.

Specification of Letters Patent.

Patented May 14, 1912.

Application filed September 28, 1911. Serial No. 651,694.

To all whom it may concern:

Be it known that I, GEORGE L. ROLLINS, of Bridgewater, in the county of Plymouth and State of Massachusetts, have invented 5 certain new and useful Improvements in Reinforced Insoles, of which the following is a specification.

This invention relates to inner soles for welted boots and shoes, and particularly to 10 that class of inner soles in which the rib receiving the stitches of the inseam is reinforced by a stay of any material suitable for the purpose, for instance, a textile fabric such as duck or other cloth, or other material.

My particular object is to supply a want 15 which has not as yet been met by reinforced inner soles as heretofore made, namely, to supply a sole having the desirable characteristics as follows:—first, the full stiffness and strength of the stock in its original condition at the edge of the insole; second, a flat and smooth surface over the entire area bounded by the rib; third, additional reinforcement at the rib; fourth, the absence of 20 a groove or gutter on the face of the sole opposite to that from which the rib projects and following the course of the rib. In short it is my object to combine all of these 25 features in a single sole.

In the accompanying drawings I have 30 illustrated a sole embodying my invention, and therein—

Figure 1 is a cross section of the sole. Fig. 35 2 is a perspective view of the sole. Fig. 3 is a cross section illustrating a slight modification.

The same reference characters indicate the 35 same parts in all the figures.

Referring to the drawings, *a* represents an 40 inner sole which is ordinarily made of leather, but sometimes made of leather board, pasteboard, or some such material less expensive than leather. Formed integrally 45 on the sole is a lip or rib *b* provided to receive the stitches which unite the upper leather and welt strip to the inner sole. This lip or rib is formed by cutting a chan-

nel, represented by *c* in the face of the sole, and turning up that part of the material of 5 the sole which lies over the channel, at right angles to the plane of the sole. The channel *c* is cut from a line well within the edges of the sole, following the outline thereof more or less closely, and extending part way 55 only to the edges. In other words, the inner limit of the channel is distant from the edge of the sole an amount equal to the height of the rib plus the extension of the sole outside of the rib. The rib is thus formed entirely 60 of material cut from the face of the sole back or inside of the base of the rib. The reinforcing strip or stay strip *d*, preferably of some such textile fabric as duck, is laid in the angle between the inner face of the 65 rib and the bottom of the channel *c*. The width of the strip is approximately equal to the height of the lip plus the width of the channel, and its thickness is about equal to the depth of the channel. It thus lies in the 70 channel practically filling the same, and against the inner face of the rib. It is cemented or otherwise firmly secured to the surfaces against which it bears, and thus reinforces the rib. An additional reinforcement is provided by a sheet or layer *e* preferably also of cloth, which is placed against 75 the face of the sole in the area bounded by the rib and overlies this face and also that portion of the stay strip *d* which lies in the 80 channel. Adjacent to the rib it is turned up so that it lies against the inner face of the rib, or rather of the stay strip which lies against the rib. In other words the turned-up part of the reinforcing sheet lies against 85 the composite rib formed of the lip *b* and the turned up edge of the straight strip *d*. In the preferred form of the invention, the reinforcing sheet *e* is of sufficient dimensions to enable it to be carried over the rib, down 90 upon its outer side, and out to the edge of the sole beyond the rib, as shown in Fig. 1. It is secured by cement or the like against the faces with which it comes in contact. The reinforce *e* thus adds to and strengthens 95 the entire face of the sole and makes of the

stitch-receiving rib a composite rib formed of one thickness of leather (or of whatever other substance the body of the sole may be composed) and three thicknesses or layers of 5 fabric.

- It is not essential that the reinforce *e* should extend either quite to the edges of the sole, or even outside of the rib, and in another embodiment of the invention, as 10 illustrated in Fig. 3, I have shown the edges of the reinforce as terminating at the top of the rib. This form of the invention, however, is the same in respect to the additional reinforce or stay which lies between 15 the leather core of the rib and the external reinforce. Both forms of the invention therefore include a supplemental stay or reinforcement within the external reinforce- 20 ment.
- 20 The most important purpose served by the supplemental reinforce or stay *d* is to fill up the channel *c* and make the surfaces of the sole to which the outer reinforce is applied flat and continuous. The other pur- 25 pose is to provide additional strength in the stitch-receiving rib.

I am aware that many forms of insoles provided with stitch-receiving ribs have been made. Such ribs where they are integral 30 with the sole are formed either by channeling or slitting inward from the edge of the sole, or from near the edge, or by channeling outward from a line relatively far within the boundaries of the sole. When the 35 rib is formed by the first method the edge of the sole, which is needed to hold the upper down to the welt and give the proper shape to the upper, is weakened, so that this purpose is imperfectly served. The addition 40 of a reinforce on the feather edge of the sole does not restore the strength lost by such channeling, and only imperfectly overcomes the objections to soles made in this way. On the other hand soles which 45 are channeled inside of the rib are weakened at this part so that what is termed a gutter forms in the opposite face of the sole. Such opposite face is the one which is exposed inside the shoe, and against which the foot 50 of the wearer bears. The gutter which develops through the weakening of the outer face of the sole by the channel inside the lip is objectionable for many reasons. No method of reinforcing a sole channeled in 55 this manner has been able to overcome this defect, so far as I am aware. By the improvement which I have made the channel is filled by the supplemental strip, and the reinforcing sheet which lies over it is not depressed or offset into the channel. Con- 60sequently the outer reinforce is smooth throughout its entire extent between the

ribs, and the pressure applied through the outer sole acts through the reinforce and the supplemental or intermediate strip to 65 resist the tendency for the gutter to be formed. Thus the objection incident to both types of insole which I have described are overcome in my improved sole. My invention therefore provides a sole which 70 has the full strength outside of the rib, is of substantially uniform thickness throughout its entire width, both inside and outside the rib, is without the objectionable gutter on the face exposed within the shoe, and is 75 stronger than heretofore. The last named feature is a very important and valuable one, for it avoids a very real danger of spoiling the shoe. Sometimes it happens that in sewing the upper and welt to an 80 inner sole of the "Gem" type, that the cloth reinforce tears. Such a thing is less liable to happen with my insole, because the inner reinforce as well as the outer reinforce takes 85 the stitch.

I wish it to be understood that my invention is applicable to insoles of which the body is made of any material now known to be, or which may be found suitable for 90 making insoles, and of which the reinforcing members are also of any material suitable to the purpose, whether cloth, leather, or other material.

Wherever in the description and claims I refer to the inner side of the rib or the 95 inner face of the rib, or define a location as being inside the rib, I mean the side or face of the rib away from the edge of the sole and toward the center thereof.

I claim,—

1. An insole having a lip rising from the face thereof and having a channel in the same face inside the lip, a reinforcing strip filling such channel and lying beside the lip, and a reinforce overlying the sole, the 105 strip, and the lip.

2. An inner sole having an upstanding lip and having a channel of substantially uniform depth which has a distinct inner boundary, formed in one face inside of the 110 lip, and a reinforce strip lying in and substantially filling said channel and lying against the inner face of the lip with its inner edge substantially coincident with such boundary.

3. An insole having a lip rising from one face thereof and having a channel in the same face located within the lip, a reinforcing strip lying against the inner side of the lip and the bottom of the channel, of such width and thickness as substantially to fill the channel, and a reinforce overlying the sole and strip, and being turned up on the 120 inner side of the lip.

4. An insole having an integral lip turned up at right angles to the plane of the sole and having a channel located within the lip, and having also its full strength outside
5 the said lip, a reinforce lying on the surface of the sole inside the lip and turned up at the rib, and a supplemental reinforce intermediate the first-named reinforce and rib, lying beneath the first-named reinforce | immediately adjacent to the base of the rib, 10 and co-extensive in width with the channel.
In testimony whereof I have affixed my signature, in presence of two witnesses.

GEORGE L. ROLLINS.
